DES. 2092

John Letchworth, of Philadelphia, Penna.
Letters Patent No. 2092 - Dated June 18, 1865.
Design for a Lamp Chimney.

The schedules referred to in these Letters Patent and making part of the same.

To all whom it may concern:

Be it known that I, John Letchworth, of Philadelphia, County of Philadelphia, State of Pennsylvania, have invented or produced a new and original design for a lamp Chimney, and I do hereby declare the accompanying drawing with the following explanation of the same to form a full clear and exact description of the said design.

My lamp chimney is, as regards external form, similar to ordinary chimneys with this exception that there is an annular recess or indentation at or near the point indicated in the accompanying drawing.

Claim

The shape and configuration of the lamp chimney substantially as represented in and by the accompanying drawing.

Testimony whereof I have signed my name to this specification in the presence of two subscribing witnesses.

Witnesses:

Charles E. Foster,

John Letchworth.

J. W. John White,
